Ronald Nicol, 316 McAdoo Ave.,
Trenton, N.J. 08619

Original design application July 1, 1971, Ser. No. 159,104, now Design Patent No. 227,903. Divided and this application Apr. 19, 1973, Ser. No. 352,712

Term of patent 14 years

Int. Cl. D13—03
U.S. Cl. D26—13 R

Fig. 2.

Fig. 3.

FIG. 1 is a side elevational view of a handle adapter for a circuit breaker;

FIG. 2 is a front elevational view;

FIG. 3 is a bottom plan view; and

FIG. 4 is a top plan view.

The portions of the figures shown in broken lines are shown for illustrative purposes only.

This is a divisional application of design application Ser. No. D. 159,104, filed July 1, 1971, now Pat. No. D. 227,903, July 4, 1973.

I claim:

The ornamental design for handle adapter for a circuit breaker, as shown and described.
